Primary Examiner — Ricky Pham*(74) Attorney, Agent, or Firm* — Beeson Skinner Beverly, LLP(57) **CLAIM**

The ornamental design for a garlic roaster, as shown and described.

DESCRIPTION

FIG. 1 is a top perspective view of a garlic roaster showing our new design;

FIG. 2 is a top plan view thereof;

FIG. 3 is a left side elevational view thereof;

FIG. 4 is a bottom plan view thereof;

FIG. 5 is a right side elevational view thereof;

FIG. 6 is a front side elevational view thereof; and,

FIG. 7 is a back side elevational view thereof.

The broken lines showing of a handle for the top of the roaster are for illustrative purposes only; the broken lines form no part of the claimed design.
